UNITED STATES PATENT OFFICE

2,536,522

ELECTRIC SWITCH

Allan H. Wilson, Arcadia, Calif., assignor to
Zinco Electrical Products Company, Los Angeles, Calif.

Application May 14, 1949, Serial No. 93,327

7 Claims. (Cl. 200—50)

1

This invention relates generally to circuit makers and breakers, and more particularly to electric switches of the enclosed, knife blade type.

It is the practice in modern industrial switchboard installations, to provide a cabinet containing bus bars from the feeder lines and adapted to accommodate a number of switch units for controlling the supply of current from the switchboard to various locations on the property. These switch units, which are embodied in protecting boxes or casings of various sizes depending on the ampere rating of the switch, may be interchangeably mounted in the cabinet and plugged into the bus bars to electrically connect same to stationary contacts of the switch, all to the end of greatly simplifying and facilitating the addition of switches to the board as well as the arrangement of switches thereon as the need arises.

It is an object of this invention to provide an electric unit of the above described character in which bridging contacts for the stationary contacts of the switch are movably mounted in the cover of the switch box in such manner that with the cover closed, the stationary contacts may be bridged by the cover contacts to complete the electrical circuit therethrough, or remain unbridged, according as the cover contacts are moved to an active or inactive position when the cover is open, thus enabling the switch to be either open or closed with the cover closed, and to be locked in the preselected adjusted position so long as the cover is closed, whereby locking of the cover in closed position will effectively prevent anyone from tampering with the switch, and changing its position.

Another object of this invention is to provide a switch unit as above set forth, in which a handle is movably mounted on the cover of the switch box and co-acts with a latching means to latch the cover closed when the handle is disposed compactly on the front of the cover, or to unlatch the cover for opening and closing movements by the handle when disposed in a projecting position in which the handle may be conveniently grasped to manipulate the cover.

A further object of the invention is to provide a switch unit which is structurally characterized to enable it to be competitively manufactured in quantity with the novel features of this invention embodied in the unit.

With these and other objects in view, the invention resides in the combinations, arrangements and functional relationships of elements as set forth in the following specification and

2

particularly pointed out in the appended claims. In the accompanying drawings,

Figure 1 is a view in front elevation, partly broken away, of one form of electric switch embodying this invention;

Figure 2 is a longitudinal sectional view taken on the line 2—2 of Figure 1;

Figure 3 is a transverse sectional view taken on the line 3—3 of Figure 1 and illustrating the closed position of the switch;

Figure 4 is a view similar to Figure 3 and showing the open position of the switch; and

Figure 5 is a fragmentary detail sectional view of a cover operating and latching handle embodied in the switch.

Referring specifically to the drawings, my invention in its illustrated embodiment comprises a generally rectangular box or casing B composed of a body 10 and a flanged cover 11 mounted on the body at one end thereof by means of a hinge 12, to open or close the front of the body when the box is installed in a wall or floor cabinet (not shown) of the well known plug-in type having a bus assembly into whose conductors the switch is plugged by means of conventional plug type contacts 15, 16 and 17, carried, respectively, by fuse blocks 18, 19 and 20 of electrical insulating material and projecting from the insulated back wall 21 of the box, as best shown in Figures 2 and 3.

It will be noted from Figure 2, that three conductors or bus bars 22, 23 and 24 are shown diagrammatically in cross section, as the switch illustrated is particularly adapted for use in a three-wire system, although it will be clearly understood that the switch may be used in a two-wire system as well.

The fuse blocks 18, 19 and 20 are secured to flanges 25 and 26 in the body 10 at the back thereof by screws 27 having nuts 28, and are disposed side by side in proximity to each other as shown in Figures 1 and 3. The fuse blocks are provided with the usual load lugs 29 and pairs of clips 30 and 31, for suitable cartridge fuses 32. Each load lug 29 is connected to the respective clip 31 by a conductor bar 32a, whereas each of the clips 30 is connected by a conductor bar 33 to the contact 34 of a pair of stationary contacts 34 and 35 projecting from the respective fuse block into a socket 36 in a socket member 37 of electrical insulating material spanning the fuse blocks transversely at the end of the box remote from the hinge 12 and secured to the body 10 by certain of the screws 27, as shown in Figure 1.

The stationary contacts 34 and 35 of each pair are spaced and insulated from each other by a separator 40 and are connected to the contacts 15, 16 and 17 of the line conductors 22, 23 and 24, respectively, to normally provide an open circuit at each pair of switch contacts 34, 35 between the respective line conductor and load clip 29. As this specific circuit arrangement is well known in the art and forms no part, per se, of the present invention, further detailed description will be dispensed with.

Co-actable with each pair of contacts 34, 35 is a bridging contact 51, so that for the three-wire circuit illustrated, three bridging contacts are provided and are mounted for movement on the cover 11 to occupy an active position wherein they bridge the respective pair of contacts 34, 35 when the cover is closed, or an inactive position wherein they are clear of the contacts 34, 35 in the closed position of the cover.

For this purpose a support 50 in the form of an elongated rectangular bar of insulating material, is secured by screws 52 to the inside of the cover 11 at a location which is directly opposite the socket member 37 when the cover is closed as shown. The support 50 is provided with a longitudinal guideway 53 in which is reciprocably mounted an actuator 54 for the bridging contacts 51, which is provided with a finger piece or knob 55 projecting through a slot 56 in the cover for manual actuation to shift the actuator to one extreme position or the other as shown in Figures 3 and 4. A spring-pressed ball 57 mounted in the actuator and urged against the inner side of the cover 11, co-acts with an instruck keeper lug 58 on the cover to releasably retain the actuator in either extreme position.

Pivot pins 60 are mounted at their ends in recesses 61 in the actuator 54 and are confined in such recesses by the confronting face of the support 50. Pivotally mounted on the pins are the bridging contacts 51 which are of generally U-shaped contour to provide spaced arms or blades 63 which are urged by U-shaped spring clips 64 to the contracted position shown in Figure 4, and work freely in slots 65 in the support 50. Spanning the slots 65 transversely are cams 66 in the form of fixed bars of insulating material which are straddled by the arms 63 of the respective contacts 51 and co-act therewith to positively swing the latter about the axes of the pins 60 to active or inactive position according as the actuator 54 is moved to one extreme position or the other when the cover is open. Movement of the contacts to active position is definitely limited by stop shoulders 67 on the support 50.

A handle 70 having a hand-grip 71, is pivotally mounted by pins 72 on ears 73 on the outside of the cover 11 at a location remote from the hinge 12, for swinging movement to occupy one position for use as shown in Figures 4 and 5, or a non-use position shown in Figures 1, 2 and 3. At one side, the handle 70 is extended laterally to provide a latching hook 74 working freely in a slot 75 (Figure 5) in the cover 11, for latching engagement with a keeper pin 76 in the body 10, when the handle occupies its non-use position wherein the handle rests flatly against the face of the cover, all so as to latch the cover in closed position with the handle disposed compactly on the cover.

Openings 77 and 78 in the handle and in one of the ears 73, respectively, are arranged to register when the handle occupies its non-use position.

so as to receive the hasp of a padlock (not shown) and lock the cover closed if desired to prevent any unauthorized access to the switch. The cover 11 is provided with a shallow depression 80 opposite the hand-grip 71, which enables the fingers of the operator to be readily applied to the hand-grip when the handle 70 is in non-use position, for swinging of the handle to its position for use at which it is definitely limited by engagement of a stop shoulder 81 on the hook 74 with the wall of the cover at one end of the slot 75 as clearly shown in Figure 5.

The operation of the invention is as follows:

With the cover 11 open, the bridging contacts 51 may be moved to active or inactive position as desired, by manipulation of the finger piece 55 to shift the actuator 54 to one extreme position or the other, it being clear that this motion of the actuator effects wiping engagement of one or the other of the arms 63 of the contacts 51 with the cams 66 to swing the contacts simultaneously and correspondingly about the axes of their respective pivot pins 60.

In their active position as shown in Figure 3, the lengths of the contacts 51 are in parallelism with the plane of swinging movement of the cover, so that upon closing the latter with the handle 70, the contacts 51 will enter the sockets 36 on opposite sides of the separators 40 and will be spread slightly by the tapered noses of the pairs of contacts 34, 35 against the urging action of the spring clips 64, and thus make firm electrical and mechanical engagement therewith. The handle 70 is now swung to its non-use position so as to latch the cover closed, or to lock the cover in closed position by the use of a suitable padlock.

To change the position of the contacts 51, the cover 11 is opened and the actuator 54 is shifted by the finger piece 55 to its other extreme position for co-action of the cams 66 with the arms 63 of the contacts 51 in moving the latter to their inactive position shown in Figure 4, in which their lengths extend at an obtuse angle with respect to the plane of swinging movement of the cover, with the contacts being withdrawn almost entirely into the slots 65 of the support 50. Thus, upon closing the cover, the contacts 51 will be incapable of bridging the pairs of contacts 34, 35 so that the circuits will remain broken.

From the foregoing description, it will be manifest that the circuits may be made or broken at the pairs of stationary contacts 34, 35 in the box by the bridging contacts 51 when the cover 11 is closed, depending upon whether the contacts 51 have been moved when the cover is open to their active or inactive position, and that the cover may be securely latched closed, or locked in closed position by the use of a suitable padlock.

The mechanism of the switch may thus be entirely enclosed and adequately protected against unauthorized access irrespective of whether the circuits are closed or opened by the switch, and that with the cover closed, the position of the contacts 51 cannot be changed from that to which they have been adjusted when the cover is open, thus rendering the switch tamperproof.

I claim:

1. In a switch of the class described, a box having a cover pivotally mounted thereon; a pair of insulated contacts supported in the box; a bridging contact; an actuator reciprocably mounted on said cover; means pivotally mounting said bridging contact on said actuator; and a fixed cam on the cover with which said bridging con-

tact has wiping engagement so as to be swung thereby about its pivotal mounting on the actuator to an active or inactive position according as said actuator is moved to one extreme position or another when the cover is open, for engagement of the bridging contact with said pair of contacts or disengagement therefrom accordingly, when the cover is closed.

2. In a switch of the class described, a box having a cover pivotally mounted thereon; a pair of contacts supported in the box and insulated from each other; a bridging contact having spaced contact arms; an actuator reciprocably mounted on said cover; a pivot pin carried by said actuator and on which said bridging contact is mounted; and a fixed cam on the cover, straddled by said arms of the bridging contact, for wiping co-action therewith in swinging the bridging contact upon said pivot pin to an active or inactive position according as said actuator is moved to one extreme position or another when the cover is open, for engagement of the bridging contact with said pair of contacts or disengagement therefrom accordingly, when the cover is open.

3. In a switch of the class described, a box having a cover pivotally mounted thereon; a pair of insulated contacts supported in the box; a U-shaped bridging contact providing spaced contact arms and a connecting portion at one end thereof; a support secured to said cover and having a guideway; an actuator reciprocably mounted in said guideway and having a finger piece accessible exteriorly of the cover; said actuator having alined recesses at opposite sides of said guideway; a pivot pin seated at its ends in said recesses and confined therein by said support; said connecting portion of said bridging contact receiving said pin to pivotally mount the bridging contact thereon; a fixed cam on the support, straddled by said arms of the bridging contact, for wiping coaction therewith in swinging the bridging contact upon said pin to an active or inactive position according as said actuator is moved by said finger piece to one extreme position or another when the cover is open, for engagement of the bridging contact with said pair of contacts or disengagement therefrom, accordingly, when the cover is closed; and means on the cover and actuator, co-acting to releasably retain the latter in either extreme position.

4. In a switch of the class described, the combination of: a box; a cover hinged at one end to one end of said box in such a manner as to partially close the open side of said box when in its closed position; a pair of fixed contacts supported in and electrically insulated from said box and electrically insulated from each other; an actuator supported in said cover in such a manner as to be movable along a straight line within limits with relation to said cover, a bridging contact so shaped that in its bridging position it electrically connects one of said fixed contacts with the other of said fixed contacts, said bridging contact being pivoted on said actuator; and a cam member fixed with relation to said cover and so placed as to swing said bridging contact about its pivot on said actuator as said actuator is moved from one of its limiting positions to the other.

5. In a switch of the class described, the combination of: a box; a cover hinged at one end to one end of said box in such a manner as to par-

tially close the open side of said box when in its closed position; a pair of fixed contacts supported in and electrically insulated from said box and electrically insulated from each other; an actuator supported in said cover in such a manner as to be movable along a straight line within limits with relation to said cover; a U-shaped bridging contact so shaped that in its bridging position it electrically connects one of said fixed contacts with the other of said fixed contacts, said bridging contact being pivoted on said actuator; and a cam member fixed with relation to said cover and extending between the arms of said U-shaped bridging contact, being so placed as to swing said bridging contact about its pivot on said actuator as said actuator is moved from one of its limiting positions to the other.

6. In a switch of the class described, the combination of: a box; a cover hinged at one end to one end of said box in such a manner as to partially close the open side of said box when in its closed position; a pair of fixed contacts supported in and electrically insulated from said box and electrically insulated from each other; an actuator supported in said cover in such a manner as to be movable along a straight line within limits with relation to said cover; a bridging contact so shaped that in its bridging position it electrically connects one of said fixed contacts with the other of said fixed contacts, said bridging contact being pivoted on said actuator; and a cam member fixed with relation to said cover and so placed as to swing said bridging contact about its pivot on said actuator as said actuator is moved from one of its limiting positions to the other, said parts being so proportioned that the cover can be closed with said bridging contact in either of its extreme positions about its pivot with relation to said cover.

7. In a switch of the class described, the combination of: a box; a cover hinged at one end to one end of said box in such a manner as to partially close the open side of said box when in its closed position; a pair of fixed contacts supported in and electrically insulated from said box and electrically insulated from each other; an actuator supported in said cover in such a manner as to be movable along a straight line within limits with relation to said cover; a U-shaped bridging contact so shaped that in its bridging position it electrically connects one of said fixed contacts with the other of said fixed contacts, said bridging contact being pivoted on said actuator; and a cam member fixed with relation to said cover and extending between the arms of said U-shaped bridging contact, being so placed as to swing said bridging contact about its pivot on said actuator as said actuator is moved from one of its limiting positions to the other, said parts being so proportioned that the cover can be closed with said bridging contact in either of its extreme positions about its pivot with relation to said cover.
